[57] CLAIM

The ornamental design for a diamond polishing bottom dop, as shown and described.

DESCRIPTION

FIG. 1 is a front elevational view of a diamond polishing bottom dop showing my new design;

FIG. 2 is a rear elevational view;

FIG. 3 is a top plan view;

FIG. 4 is a bottom plan view;

FIG. 5 is a left side elevational view;

FIG. 6 is a right side elevational view;

FIG. 7 is a front elevational view of a second embodiment of my new design of FIGS. 1-6; and

FIG. 8 is a rear elevational view;

FIG. 9 is a top plan view;

FIG. 10 is a bottom plan view;

FIG. 11 is a left side elevational view; and,

FIG. 12 is a right side elevational view thereof.
